INVENTOR.

*Roy Burton,
BY
Geo. P. Kimmel.*

ATTORNEY.

UNITED STATES PATENT OFFICE

ROY BURTON, OF SALEM, OREGON

MARKER

Application filed October 18, 1930. Serial No. 439,683.

This invention relates to a marker designed primarily for use in connection with ice cream bricks, but it is to be understood that a marker, in accordance with this invention may be employed in any connection for which it may be found applicable, and the invention has for its object to provide, in a manner as hereinafter set forth, a marker so constructed and arranged for marking an ice cream brick to enable one to cut the brick in slices of exact proportion.

Further objects of the invention are to provide, in a manner as hereinafter set forth, a marker for the purpose referred to which is simple in its construction and arrangement, strong, durable, compact, thoroughly efficient in its use, and comparatively inexpensive to manufacture.

With the foregoing and other objects in view, the invention consists of the novel construction, combination and arrangement of parts as hereinafter more specifically described, and illustrated in the accompanying drawing wherein is shown an embodiment of the invention, but it is to be understood that changes, variations and modifications can be resorted to which fall within the scope of the claim hereunto appended.

In the drawing wherein like reference characters denote corresponding parts throughout the several views:

Figure 1 is a top plan view of a marker in accordance with this invention.

Figure 2 is an edge elevation looking towards one side of the marker.

Figure 3 is a section on a line 3—3 Figure 1.

The marker includes a thin, flat, elongated rectangular body part 1 corresponding in length to that of the brick 2, the latter being indicated by the dotted line showing Figure 2. One end of the body part 1 is formed with a right angularly disposed flange 3, which when the marker is used abuts against one end of the brick or one side of the latter for the purpose of serving as a guide so that straight,

equi-distant lines in the form of grooves will be made across one face of the brick when the marker is drawn over such face. The marker can be constructed of any suitable material, preferably sheet metal of the desired gauge.

The body part 1 at its transverse center is formed with a transverse slot 4 which is employed to indicate the center of the brick. At that end of the body part 1, opposite the end provided with the flange 3 it is formed with an opening 5 for the purpose of hanging up the marker when the latter is not used.

One side edge of the body part 1 is formed with a set of equally spaced, integral, slightly inturned tapered projections 6 which constitute marking points. The other side of the body part is formed with a set of equally spaced, integral, slightly inturned tapered projections 7 which constitute marking points. The distance between the points 6 is materially less than the distance between the points 7. The set of marking points 6 is employed for marking the bricks for eight slices and the set of marking points 7 is used for marking the bricks for six slices. The projections are downwardly inclined with respect to the outer face of the body part 1. Each set of projections extends from one end to the other end of the body part 1.

When marking the bricks the marker is tilted upwardly slightly relative to that face of the brick which is to be marked, with the flange or guide abutting one end of the brick, and then the operator draws the marker across such face thereby providing the latter with spaced lines or marks in the form of grooves to enable the operator to cut the brick in slices of exact proportions, or in other words, to slice the brick in slices of equal thickness. If desired, each of the faces, other than the end faces of the brick can be scored or grooved and with the grooves of

one face forming continuations of the grooves
of the other faces.

What I claim is:—

In a marker for the purpose set forth, an
5 elongated, flat, thin, one-piece body part pro-
vided at one end with a right angularly dis-
posed flange and intermediate its ends with
an opening, said opening disposed centrally of
said body part, said body part further having
10 each side edge thereof provided with a later-
ally extending set of equally spaced, integral
tapered projections providing marking
points.

In testimony whereof, I affix my signature
15 hereto.

ROY BURTON.
